UNITED STATES PATENT OFFICE.

DANIEL J. PRENDERGAST, OF NEW YORK, N. Y., AND VICTOR H. SLINACK, OF PHILADELPHIA, PENNSYLVANIA, ASSIGNORS TO THE PENNSYLVANIA GLOBE GAS LIGHT COMPANY, OF PENNSYLVANIA.

STREET-LAMP.

SPECIFICATION forming part of Letters Patent No. 672,960, dated April 30, 1901.

Application filed October 15, 1896. Serial No. 608,922. (No model.)

To all whom it may concern:

Be it known that we, DANIEL J. PRENDERGAST, of New York city, New York, and VICTOR H. SLINACK, of Philadelphia, Pennsylvania, have invented an Improvement in Street-Lamps, of which the following is a specification.

Our invention has reference to street-lamps; and it consists of certain improvements, which are fully set forth in the following specification and shown in the accompanying drawings, which form a part thereof.

The object of our invention is to provide a construction of lamp, especially intended for incandescent gas-lighting, which shall be peculiarly adapted for outside work.

The following are the essential features to which our improvements are directed: The lamp proper is inclosed in a removable glass globe and comprises one or more incandescent gas-burners employing a delicate mantle of refractory material combined with an adjustable shield adapted to be moved down to inclose the mantle so as to protect it against currents of air, which would otherwise rupture and destroy it. We prefer to form this shield in such a manner that it may be adjusted without opening the bottom of the lamp, whereby the mantle may be thoroughly protected before removing the surrounding globe to any appreciable extent. We prefer, furthermore, to so form the shield that it may act as a chimney to carry off the products of combustion and direct them to the ventilating-cap. Where there are two or more burners inclosed within the same globe, we prefer to provide means for simultaneously adjusting all the shields. We prefer also to arrange above the several shields a single directing chimney-flue which shall receive the products of combustion from all of the shields when acting as chimneys and deliver the same centrally to the ventilating-cap, and thus protect the upper portion of the glass globe from being unduly heated, with the attendant danger of being cracked by rain, sleet, or snow.

A second part of our invention is comprised in the construction of the burner proper, whereby the burner and mantle are flexibly

supported upon the gas-supplying devices, the same having capacity for compensating for vibration imparted to the gas-supplying tube from any sudden jarring to the lamp-post. This improvement is especially designed to prevent the breakage of the delicate mantle, which frequently results from sudden jars, so liable to occur with lamp-posts for outside lighting.

Another improvement embodied in our improved lamp is comprised in the non-conducting packing about the exposed portion of the gas-supply pipe between the tube of the lamp-post at the base-cap of the glass globe. Our object in this construction is to provide means to prevent condensation and freezing of the contents of the gas-pipe in very cold weather, which renders the lamp defective in operation.

Another part of our invention comprises a gas-lighting pipe made Y-shaped or otherwise formed with branches leading from the main valve for conveying a flame from the base of the lamp-globe up to the burner adjacent to the mantles. By this construction the insertion of a single taper or match will light all of the burners simultaneously. The main valve is so arranged that it simultaneously supplies gas to all of the burners and to the lighting-tube and after the ignition of the burners to shut off the supply of gas to the igniting-tube, but continue to supply gas to the burners.

More specifically considered, our improvement comprehends the vertical adjustment of the said Y-shaped or branching igniting-tubes to compensate for possible variations in the elevation of the main burners.

A further portion of our invention comprehends a valve opening into the main valve-case from the outside for the purpose of introducing a solvent into the main gas-pipe close to the valve for the purpose of dissolving or thawing out the contents of said pipe when the same has become clogged in cold weather.

A further improvement embodies the base-cap of the globe, whereby the same is supported upon the gas-pipe and does not put any weight upon the globe proper. The preferred construction is such that this base-cap

can be adjusted laterally, so as to properly centralize it upon the bottom of the globe, and at the same time it acts as a support for the outside casing for the non-conducting packing around the exposed gas-pipe. The casing is extensible, so as to be capable of adjustment to suit various lengths of the gas-pipe and for irregularities in the length of the globe.

10 These various improvements defined above comprise the main features of our invention, and they, together with the details, will be better understood by reference to the accompanying drawings, in which—

15 Figure 1 is an elevation of our improved street-lamp, with the globe and ventilating-cap in section. Fig. 2 is a sectional elevation on line $x-x$ of Fig. 1, showing the details of the lamp structure on a larger scale. Fig. 20 3 is a sectional plan view of same on line $y-y$, and Fig. 4 is a sectional elevation of the main valve.

A is the lamp-post.

25 A' represents the supporting-arms, connected at the top to a ring-support A².

B is the glass globe, having a rib b, which rests upon the ring A², so as to hang down between the arms A'. This globe is open at the bottom, and at the top supports the venti-30 tilating-cap B'. A reflector or hood B² may be supported upon the ring A², if so desired.

C is the gas-pipe leading up through the lamp-post A and is fitted at the top within a main valve C'. Opening from the top of the 35 main valve is a Y-shaped gas-pipe C², upon the upper arms of which are supported the two incandescent gas-burners D D. While we have shown two gas-burners, our improvements may be employed with one or more.

40 We do not confine ourselves to any particular number of burners when considering our improvements broadly.

Referring to the construction of the burners D, E is the gas-supply pipe, having the 45 air-apertures e, which receive the air admitted through the screen F and valve C'. In practice the valve G may be omitted and the parts properly proportioned to perform their work. The screen F is supported at the bot-

50 tom by the disk F', fitted upon the top of the Y-shaped pipe C², and upon the upper part of the screen rests an inclosing plate F². By means of this screen no insects can get to the interior of the burners and clog the gas-passages. H is the gas-burner proper and is formed with a somewhat conical gas-passage h, flaring downward and loosely supported 55 upon springs I, guided upon rods i. These rods i are connected to the burner-ring H' by

60 radial arms I' and are guided in bearings H² in the base F³ below the screen. Heads or obstructions on the bottom of these rods limit the upward movement of the burner. The springs are made delicate, so that they prop-65 erly sustain the weight of the burner, together with the mantle and accessories, to permit in case of jarring of the gas-pipe and connec-

tions free movement without imparting to the burner and the mantle which it supports a positive blow.

70 J² is the mantle and is formed of the usual delicate open structure of refractory material and is supported above the burner H. Vertical guide-rods J are secured at the lower parts to the burner and at the top are attached to a guide-ring J'.

75 Arranged within the vertical rods and encircling the burner and lower part of the mantle is a conical shield or frustum K, which opens upward at the bottom to properly guide the draft of upwardly-flowing air to the burner and refractory mantle.

80 Arranged above the refractory mantle and vertically adjustable through the ring J' is a tubular shield L, having a diameter larger than the smaller part of the conical shield K 85 and having a vertical height greater than the distance from the ring-guide to the shield, so that it may be completely lowered and fit over the conical shield in a manner to thoroughly

protect the mantle from all side drafts or currents of air. The vertically-adjustable shield 90 L is provided with a bead near its upper end, by which it is supported in a suitable ring-frame L', which is attached to the upper part of a tube L², guided upon an upright guide-95 rod L³, the latter being secured to the Y-shaped tube C² at c. To adjust the shield L vertically, we provide a vertically-movable

rod M, which connects with the vertically-adjustable tube L² and extends through the 100 base-cap N, and a suitable clamp m, comprising a guide-aperture and clamp-screw. By this means the vertically-adjustable shields may be raised and clamped in the elevated position shown or may be lowered to completely inclose the mantle without opening or removing the globe B.

105 In the foregoing description of the burner we have described our improvements with reference to a single burner; but where there are two or more burners these parts are simply duplicated and both or all of the tubular shields are simultaneously raised and lowered by the same adjusting-rod M.

110 Arranged above the tubular shields L is a centralizing-chimney T, which has a flaring lower part at t to insure any or all products of combustion passing upward from the tubes L and directing the same centrally into the 115 ventilating-cap B'. The upper part of the centralizing-chimney is provided with straps T', which extend upward and are hooked over the edges of the apertures of the ventilating-cap, as clearly shown. In this manner the chimney T is centrally supported and easily

120 removable when desired. By this means the hot products of combustion are conveyed away from the upper portion of the glass globe, and as air-currents may freely pass from the base upward and between the globe 125 and centralizing-chimney the glass is kept fairly cool and therefore not liable to become cracked in cold and stormy weather.

The base-cap N consists of an open casting,

practically of a diameter to fit the opening in the bottom of the glass globe B. The base-cap is provided with three or more radial adjustable guides n, which do not necessarily 5 clamp the globe. This cap is provided with glass windows N' to permit the rays of light to pass freely down around the base of the lamp-post and avoid the casting of deep shadows. The base-cap is also provided with 10 an aperture N² for entering the igniting taper or match, adjacent to which is pivoted a door N³, which may be moved laterally to open or close the aperture. The center of the cap is made with an enlarged opening and is provided 15 with three or more clamping-screws N⁴, adapted to clamp upon the central gas-pipe C, and by means of which the cap may be centered relatively to the base of the globe B or to the gas-pipe, as desired.

20 O is a piece of tube secured to the base-cap N by the clamping-screws and is adapted to telescope with a second section of tube O', resting upon the top of the lamp-post and within the socket a, to which the upright 25 arms A' are secured at their base.

O² is a packing of asbestos or other non-conducting substance interposed between the tubes O' and the gas-pipe C.

To one side of the main valve C' is arranged 30 a tubular arm P', the end of which is controlled through a port p in the valve by means of a rotary reciprocating valve c, which is operated by an arm C⁴. The arms C⁴ may be moved by inserting a hook or manipulating 35 device through the aperture N² in the base-cap N. Supported in the free end of the tubular pipe P' and adjustable vertically therein at P is an upright tubular portion P², which branches into two or more branches P³, leading 40 up to the burners H H. The several pipes P² and P³ are provided with a series of small gas-apertures along their length and for the purpose of causing a flame to travel from one end to the other up to the burners. We prefer 45 to form the end of the tubular portion P' also with apertures, so that the flame may ignite close to the opening N² in the base-cap and be caused to travel up to all of the burners simultaneously. The main valve C' supplies 50 gas to the burners simultaneously with the supply of gas to the pipes P', P², and P³, so that the flame may be supplied to the main burner without opening the glass globe or lowering the base-cap. When the main valve 55 is moved to its fullest extent, the gas continues to be supplied to the burners, but is shut off from the pipe P'. The main burners continue to burn, but the flames on the pipes P', P², and P³ are extinguished.

60 It frequently happens that the main supply-pipe C becomes clogged by the freezing of the liquids produced by condensation, and it becomes necessary under such conditions to thaw out the pipe by some suitable means.

65 It being impractical to dismantle the parts of the structure, and especially so without liability of injury to the mantles, we provide

a small valve or plug S, adapted to close an entrance into the gas-pipe through the main valve C'. By removing this plug or valve we 70 are permitted to pour into the pipe a suitable solvent or liquid for thawing out the same, and thus permitting the rectifying of the defects without the least danger to the lamps as an entirety and without loss of time, which 75 would result upon any attempt to dismantle the parts.

While we prefer the specific constructions herein set out, we do not confine ourselves to the details, as they may be modified in various ways without departing from the principle of our invention.

What we claim as new, and desire to secure by Letters Patent, is—

1. In a street-lamp, the combination of a 85 gas-burner, an incandescing mantle of refractory material above the burner, an outer removable glass globe, a vertically-adjustable tubular shield adapted to be raised above or moved down over the mantle to inclose it, 90 means for adjusting the said tubular shield from the outside of the globe whereby the shield may be adjusted without removing the globe, a ventilating-cap supported upon the top of the glass globe, and a centralizing stationary chimney arranged above the adjustable tubular shield and extending below the cap and within the glass globe whereby an air-passage is permitted between the glass globe 95 and centralizing-chimney. 100

2. In a street-lamp, the combination of two or more gas-burners, a single glass globe inclosing said burners, a separate mantle of refractory material supported above each burner, vertically-adjustable shields for each 105 of the burners whereby they may be lowered to completely inclose the refractory mantles, and a single centralizing-chimney arranged above all of the vertically-adjustable shields for delivering the products of combustion centrally to the ventilating-cap and forming an air-passage between the glass globe and the chimney. 110

3. In a street-lamp, the combination of two or more gas-burners, a single glass globe inclosing said burners, a separate mantle of refractory material supported above each burner, vertically-adjustable shields for each of the burners whereby they may be lowered to completely inclose the refractory mantles, 115 a single centralizing-chimney arranged above all of the vertically-adjustable shields for delivering the products of combustion centrally to the ventilating-cap and forming an air-passage between the glass globe and the chimney, and a single adjusting device extending to a point outside the globe for simultaneously adjusting all of the vertically-adjustable shields. 120

4. In a street-lamp, the combination of two 130 or more gas-burners, a single glass globe inclosing said burners, a separate mantle of refractory material supported above each burner, vertically-adjustable shields for each

- of the burners whereby they may be lowered to completely inclose the refractory mantles, a conical shield encircling the burners and the base of the refractory mantles and of 5 smaller diameter at the top than the diameter of the vertically-adjustable shield so as to be received within them when they are lowered, and a single centralizing-chimney arranged above all of the vertically-adjustable shields 10 for delivering the products of combustion centrally to the ventilating-cap and forming an air-passage between the glass globe and the chimney.
5. In a street-lamp, the combination of a 15 lamp-post, a gas-pipe extending above the lamp-post and leading to the burners, a glass globe surrounding the burners and provided at the base with a cap, a non-conducting packing surrounding the gas-pipe between the top 20 of the lamp-post and the bottom of the globe base-cap, and a telescopic tubular casing enclosing the gas-pipe and packing extensible as to its length, the lower portion of which is supported upon the lamp-post and the upper 25 portion upon the base-cap of the globe, the said casing being adapted to be adjusted to suit different heights between the top of the post and base-cap for the globe.
6. In a street-lamp, the combination of the 30 gas-pipe, a gas-burner thereon, an inclosing glass globe, a main valve to supply gas to the burners, an igniting burner-pipe extending from the main valve continuously to the main burner, and a vertically-adjusting extension device connected with the valve-casing 35 at the extreme lower end of the burner-pipe for adjusting the upper end of the igniting-tube relatively to the main burner.
7. In a street-lamp, the combination of the 40 main gas-supply pipe, two or more burners arranged to receive gas therefrom, an igniting burner-pipe leading from the main gas-supply pipe and provided with branching pipes perforated throughout their length leading to the 45 burners respectively whereby both burners may be ignited simultaneously, incandescent mantles supported above the burners and wholly above the said branching pipes so that the gas may be ignited before passing over 50 the mantles to avoid a downward explosion with the danger of breakage of said mantles, and a single-valve device for simultaneously controlling the gas to both burners and both igniting burner-pipes and whereby the gas 55 supply to the igniting burner-pipe may be wholly cut off when the supply of gas to the main burner is wholly turned on.
8. In a street-lamp, the combination of the 60 gas-supply pipe, two or more burners arranged to receive gas therefrom, a single

valve to control the gas to said burners simultaneously, a continuous perforated igniting burner-pipe leading from the main valve and branching to each of the burners whereby each of the burners may be ignited simultaneously and means at the bottom of the branching pipe to adjust all of the branching pipes simultaneously vertically with reference to the other burners. 65

9. In a street-lamp, the main gas-pipe, and 70 air and gas mixing chamber and burner-tube secured to the upper part of the gas-pipe, in combination with a burner proper having a downwardly-extending enlarged tubular portion loosely receiving the burner-tube, elastic supports for the burner whereby it is sustained independently of the burner-tube, a refractory mantle supported over the burner, a support for the mantle connected to and movable with the burner, a stationary igniting-tube leading from the main gas-pipe and 75 extending upward to the burner but independent of it so as not to interfere with its movement, and valve devices for controlling the gas-supply to the mixing-chamber and 80 burner-tube and to the igniting-tube simultaneously or to the mixing-chamber and burner alone. 85

10. In a street-lamp, the combination of the main gas-pipe, an air and gas mixing chamber and burner-tube secured to the upper part of the gas-pipe, a burner proper having a downwardly-extending enlarged tubular portion loosely receiving the burner-tube, elastic supports for the burner whereby it is sustained independently of the burner-tube, a refractory mantle supported over the burner, a support for the mantle connected to and movable with the burner, a stationary igniting-tube leading from the gas-pipe and 90 extending upward to the burner but independent of it so as not to interfere with its movement, valve devices for controlling the supply to the mixing-chamber and to the igniting-tube simultaneously or the mixing-chamber alone, and an inclosing screen surrounding the air-apertures to the mixing-chamber supported independently of the burner and its elastic support. 95 100 105

In testimony of which invention we here- 110 unto set our hands.
